DESIGN FOR A DRAWER PULL

Roy L. Peat, Huntington Park, Calif., assignor to
Plastic and Die Cast Products Corporation, Los
Angeles, Calif., a corporation of California

Application August 9, 1940, Serial No. 94,344

Term of patent 3½ years

To all whom it may concern:

Be it known that I, Roy L. Peat, a citizen of the United States, residing at Huntington Park, in the county of Los Angeles and State of California, have invented a new, original, and ornamental Design for a Drawer Pull, of which the following is a specification, reference being had to the accompanying drawing, forming part thereof.

In said drawing:

Fig. 1 is a front elevation;
Fig. 2 is an end elevation;
Fig. 3 is a plan; and
Fig. 4 is a perspective view of a drawer pull showing my new design.

I claim:
The ornamental design for a drawer pull, as shown.

ROY L. PEAT.
